UNITED STATES PATENT OFFICE.

JAMES BARRETT, OF BEALLSVILLE, OHIO, ASSIGNOR OF A PART TO BENJAMIN DENNIE, OF SAME PLACE.

CAR-COUPING.

SPECIFICATION forming part of Letters Patent No. 279,317, dated June 12, 1883.

Application filed August 16, 1882. (No model.)

To all whom it may concern:

Be it known that I, JAMES BARRETT, of Beallsville, in the county of Monroe and State of Ohio, have invented a new and Improved 5 Car-Coupling, of which the following is a full, clear, and exact description.

This invention relates to certain improvements in my new and improved car-coupling shown and described in Letters Patent No. 10 259,792, which were granted to me June 20, 1882, and has for its object to provide means whereby a close coupling of the cars may be effected.

My invention consists in the employment of 15 a coupling pin or plate of considerable length pivoted in the upper forward end of the draw-head and inclining downward and backward into the throat of the draw-head, the inner and lower end of the pin or plate being suitably 20 notched for engaging with the connecting-link, as hereinafter fully described.

Reference is to be had to the accompanying drawings, forming part of this specification, in 25 which similar letter of reference indicate corresponding parts in both the figures.

Figure 1 is a sectional elevation of a pair of draw-heads made in accordance with my present invention, and Fig. 2 is a perspective view of the long coupling pin or plate. 30 A represents the draw-heads; B, the connecting-link; and C represents the coupling pins or plates. The draw-heads A are enlarged slightly at the outer ends, as shown at b, and are slotted from the upper side through

35 to the throats c thereof, as shown at d. The coupling pins or plates C are pivoted in these slots upon the pins e, and from the said pins they incline downward and backward into the throats c, as shown in Fig. 1. The inner ends 40 of the said coupling pins or plates are each notched, so as to form the point or toe i and the offset i'. These offsets i', when the cars are coupled, engage with and hold the connecting-link, and the points or toes i are adapted to

45 rest upon the upper side of the link when coupled, as shown in dotted lines in Fig. 1, to prevent the plates dropping down too far through the link and becoming locked. The offsets or notches i' are made slightly inclined 50 toward head of pin, as shown, so that the

plates may be easily disengaged from the links for uncoupling the cars and to permit closer coupling.

D D are levers pivoted in the uprights g g for raising the plates or pins C for uncoupling 55 the cars. These levers are attached to the said plates or pins at their outer ends by means of the eyebolts h, and to their outer ends are attached the rods or levers E, which lead to the top, sides, or platform of the cars, where they 60 can be operated for uncoupling the cars without danger. When the cars are uncoupled and the connecting-link B comes out of the draw-heads, the coupling pins or plates C will drop down and rest at their inner ends upon 65 the bottom of the throats c, and the pin is again ready for recoupling when the cars meet together. The entrance of the link into the draw-head of the opposing car will raise the inner end of the pin or plate and pass beyond 70 the offset i', whereupon the pin or plate will drop into the link, as shown in dotted lines in Fig. 1, and thus automatically couple the cars. For uncoupling, it is only necessary to press down upon the upper end of one of the levers D, 75 which will raise the inner end of the pin or plate C, and thus release the connecting-link. By this construction it will be seen that the link B will be held by the connecting plates or pins, so as to make a close coupling, leaving 80 only sufficient play between the rounded ends of the draw-heads for the cars to pass around curves in the road without breaking, bending, or otherwise injuring the connecting-link.

Suitable spiral springs may be placed under 85 the platform of the cars in a vertical position, the lower ends thereof resting upon the notched ends of the coupling-plates for keeping them from bounding out of place when the cars are in motion; and suitable buttons may be provided for holding the ends of the levers E, or other uncoupling-lever to keep them in place while the cars are in motion.

Having thus described my invention, what I claim as new, and desire to secure by Letters 95 Patent, is—

1. The combination, with draw-head A, provided with the slot d in its upper side, of the coupling-plate C, pivoted in the said slot, and having its inner end notched to form the toe i 100

and the offset i' , substantially as shown and described.

2. The combination, with the draw-head A, having its outer end enlarged, as at b, and provided with the slot d, of the coupling-plate C, pivoted in the said slot, and provided with the toe i, and the offset i' at its inner end, and

means for raising the inner end of said coupling-plate, substantially as herein shown and described.

JAMES BARRETT.
